Attorneys.

UNITED STATES PATENT OFFICE.

JAMES M. WALSH, OF MILWAUKEE, WISCONSIN, ASSIGNOR TO WALSH HARNESS COMPANY, OF MILWAUKEE, WISCONSIN, A CORPORATION OF WISCONSIN.

BLINDER.

1,282,335.

Specification of Letters Patent. Patented Oct. 22, 1918.

Original application filed March 10, 1915, Serial No. 13,307. Divided and this application filed December 24, 1915. Serial No. 68,517.

To all whom it may concern:

Be it known that I, JAMES M. WALSH, a citizen of the United States, residing at Milwaukee, in the county of Milwaukee and 5 State of Wisconsin, have invented certain new and useful Improvements in Blinders, of which the following is a specification, reference being had to the accompanying drawing, forming a part thereof.

10 This invention relates to bridle blinders, blinkers or winkers, and its main objects are to simplify and improve the construction thereof and to effect a material saving in leather.

15 It consists in the peculiar construction, arrangement and combination of parts as hereinafter particularly described and finally pointed out in the claims.

20 In the accompanying drawing like characters designate the same parts in both figures.

Figure 1 is an outside view of a blinder with a portion of a cheek strap constructed in accordance with the invention, a portion 25 of the leather being broken away to show parts of some of the reinforcing wires in full; and Fig. 2 is a section on the line 2—2, Fig. 1.

20 The blinder *a*, consists of a single thickness of leather and is preferably formed integrally with a cheek strap or band *b* or section thereof, a portion of which is shown in Fig. 1.

35 The blinder is reinforced and stiffened by wires *c*, inserted through the edges of the leather between and parallel with its opposite faces. The wires *c*, which are primarily straight, are inserted through the edges of the leather while it is clamped or 40 held between substantially flat or plain faced jaws, which are grooved opposite the intended location of the wires to allow the leather to spread where the wires are inserted therein and to facilitate their insertion, the outer ends of the wires being driven into the leather far enough so that the leather will close over and conceal them, as shown by the drawing.

45 To facilitate the insertion of the reinforcing wires, holes therefor may be formed

with an awl, punch or similar instrument in the leather while it is held between the jaws. When the blinder is formed integrally with a cheek strap as shown, some of the reinforcing wires are inserted through the rear edge 55 of the cheek strap and pass therefrom into the blinder.

The cheek strap may be further reinforced and prevented from twisting adjacent to the blinder by short transverse reinforcing wires 60 *d*, as shown in Fig. 1.

65 The main reinforcing wires *c*, are preferably disposed radially with relation to the blinder *a*, and extra wires *c'* are preferably employed to produce a more inflexible connection between the blinder and cheek strap.

70 After the reinforcing wires have been thus inserted in the leather, the blinders are pressed between suitable dies into any desired form, such, for example, as the concavo-convex form shown in Fig. 2, and indicated by shading in Fig. 1, the wires being sufficiently annealed to retain the form into which they are bent by this operation.

75 Various changes in minor details of construction and arrangement of component parts of the device may be made without departure from the principle and scope of the invention as defined in the following claims.

80 The application is a division of my application Serial No. 13,307, filed March 10, 1915.

I claim:

85 1. A curved blinder consisting of a single thickness of leather reinforced by wires between and parallel with its opposite faces, and transverse to its margin adjacent to which the wires terminate at one end, said wires being bent to correspond with the form 90 of the blinder.

95 2. A blinder consisting of a single thickness of leather, formed integrally with a cheek strap section and reinforced by wires passing transversely through the cheek strap section into the blinder between and parallel with opposite faces of the leather.

100 3. A blinder consisting of a single thickness of leather and formed integrally with a cheek strap and reinforced by wires in-

serted through the edges of the leather between and parallel with its opposite faces, some of the wires passing from the cheek strap into the blinder and the cheek strap being reinforced adjacent to the blinder by transverse wires inserted therein between its inner and outer faces.

Copies of this patent may be obtained for five cents each, by addressing the "Commissioner of Patents, Washington, D. C."

In witness whereof I hereto affix my signature in presence of two witnesses.

JAMES M. WALSH.

Witnesses:

PAUL E. HERB,
A. H. FLATLEY.
